UNITED STATES PATENT OFFICE.

JACOB F. LUCKHARD, OF SEBEWAING, MICHIGAN.

FOWL-CATCHER.

933,257.

Specification of Letters Patent.

Patented Sept. 7, 1909.

Application filed May 22, 1907. Serial No. 375,017.

To all whom it may concern:

Be it known that I, JACOB F. LUCKHARD, citizen of the United States, residing at Sebewaing, in the county of Saginaw and State 5 of Michigan, have invented certain new and useful Improvements in Fowl-Catchers, of which the following is a specification, reference being had therein to the accompanying drawing.

10 My present invention relates to improvements in fowl catchers, and has special reference to a catcher mounted upon the end of a handle in such a manner as to be allowed to entrap the leg of a fowl, and at the 15 same time, allow the fowl to move and cause the catcher to rotate without injuring or breaking the fowl's leg. That is, the catching members are swivelly or rotatably mounted upon a rod or shaft, which in turn 20 is secured to one end of a pole or handle.

To more clearly illustrate my invention, attention is invited to the accompanying drawings, in which:—

Figure 1 is a top plan view of the catcher, 25 attached to a handle, the jaws of the catcher being shown in full lines as open, and in dotted lines as nearly closed. Fig. 2 is a side elevation of the catcher, taken from the adjusting side thereof. Fig. 3 is a section 30 taken on line $x-x$, Fig. 1. Fig. 4 is a longitudinal section through the catcher, and Fig. 5 is a detail illustrating the trigger and spring of my device removed.

Referring to the drawings:—the numeral 35 1 designates the handle or pole, in which is stationarily mounted the pin or shaft 1', which is further provided with a head or stud 1'', the purpose of which will presently appear. My catcher 2, is rotatably or swiv- 40 elly mounted upon this pin or shaft, and is held against outward movement by means of the head or stud 1''. The catcher, as shown, consists of the two members or plates 3 and 4, which are provided with the in- 45 turned ends 3' and 4', respectively. The ends 3' and 4' are provided with alined openings, to fit rotatably or swivelly upon the shaft 1', the plate or cross-piece 6, being secured to each plate, to act both as a spac- 50 ing means for the plates, and as it is pro- 55 vided with an opening therethrough, which fits loosely upon the shaft 1', near its head 1'', it serves as an additional bearing for the catcher, so that should a fowl have its leg caught in the space or slot d between the outer ends 5, of the members, and tussle,

struggle or flap to free itself, the members will rotate about the shaft 1', and thus offer so small resistance, as to not injure or break the leg, as would be the case, if the members 60 were not swiveled.

Each plate or member, is constructed similarly with the broad portion a , having the right angled inwardly turned ends 3' and 4', the body of the plates being tapered to 65 toward the extreme ends or terminals 7 and 8, which are formed by compressing the edges c , upon themselves. This provides the receptacles with the walls 10 for the devices, which closes the slot or space d , between the 70 plates. These receptacles 10, are each provided with the slots or openings 13 and 14, respectively, the slot 14, having pivotally mounted therein the trigger or barrier 11, whose inner end 12, is adapted to enter the 75 slot 13, and thus form a locked barrier to the slot d . In order to retain the trigger or barrier in this position, so that the end 12, is held against the forward wall of the slot 13, and given a tension in that direction, I 80 employ the spring 11', whose free end fits in the notch or recess 11'', of the barrier, and bears against the abutment e . By this construction it will be seen that should the device be projected toward the leg of a fowl, 85 that the outwardly turned portions 15 of the terminals of the members 3 and 4, will guide the device, so that the leg of the fowl will enter the slot d , the barrier being struck, and by such striking, the tension of the spring is 90 overcome, so that barrier is moved rear- 95 wardly and into the slot 14, allowing the fowl's leg to pass farther within the slot d . After the leg has passed the inner end of the slot 14, the spring 11' acts upon the re- 100 leased barrier, and causes the same to as- sume the position shown in Figs. 1 and 3, and thus bars the slot, and prevents the fowl's leg from exit through the slot. Should the fowl struggle or flap, the catcher 100 being swivelly mounted upon the shaft 1', will turn with the fowl, and thus in no way injure or break the fowl's leg.

Should it not be desired to cause the fowl's leg to strike and remove the barrier, I at- 105 tach a cord 17 to the arm 18, of the trigger, and by manipulating the cord, the trigger may be held open, until after the fowl's leg has passed well within the slot, at which time, the cord is released and the trigger 110 closes the slot d .

In order to regulate the width of the slot

d, to cause it to assume a position as shown in either full or dotted lines, Fig. 1, I employ a screw 19, which passes through both plates, and is engaged by the thumb-screw 5 20, which is manipulated to close or allow the plates to spread apart.

What I claim, as new, is:—

A fowl catcher, comprising a handle, a shaft stationarily mounted in one end thereof, 10 two members secured together at one end and swivelly mounted upon the shaft at said

end, the other ends being separated by a slot, means for regulating the width of said slot, and a spring actuated barrier for normally closing said slot.

In testimony whereof I affix my signature in presence of two witnesses.

JACOB F. LUCKHARD.
